John E. Hubbard

UNITED STATES PATENT OFFICE.

WALTER FRANCIS KEENAN, JR., OF PELHAM, NEW YORK, ASSIGNOR TO FOSTER WHEELER CORPORATION, OF NEW YORK, N. Y., A CORPORATION OF NEW YORK.

SUPERHEATER BOILER.

Application filed March 31, 1924. Serial No. 703,061.

The primary object of the present invention is to make a simple and effective combination of a superheater with a water tube boiler of the type comprising a pair of horizontal steam and water drums spaced relatively widely apart and connected by horizontal circulating pipes, and also comprising horizontal water drums and water tubes connecting the water drums to one another and to one of the steam and water drums. A further object of the invention is to provide an effective combination with a boiler of the type described and its superheating provisions, of an economizer so as to obtain a relatively high thermal efficiency with a combination structure which is compact and relatively simple and durable and has provisions for ready inspection, repairs and renewals of the parts of the boiler with which such provisions are most important.

Of the drawings:

Fig. 1 is a sectional elevation of a portion of the boiler;

Fig. 2 is a partial section on the line 2—2 of Fig. 1;

Fig. 3 is a view taken similarly to Fig. 2 but on a larger scale, showing a portion only of the apparatus shown in Fig. 2; and

Fig. 4 is an elevation taken similarly to Fig. 1 but on a larger scale illustrating details of construction.

The boiler shown in the drawings comprises two steam and water drums A and B located with their axes approximately at the same level, and connected by an upper row of circulating tubes C which have horizontal body portions and down-turned end portions, and by lower circulating tubes D and E.

The tubes E comprise a short down-comer portion leading from the drum A and a longer upwardly inclined portion leading to the drum B so that the circulation through it is from the drum A to the drum B. The tubes D are generally similar to the tubes E but have their down-comer portions connected to the drum B and pass water from the latter to the drum A. Located beneath the drum B is a mud drum G connected to the drum B by a bank of tubes H the body portions of which are approximately vertical. Located beneath the drum A is an upper water drum I connected to the drum G by an inclined bank of tubes J and connected to the drum B by a bank of inclined tubes F. The feed water is introduced into the

drum B through the feed water supply connection K and steam is withdrawn from the steam and water drum A through the steam pipe K¹⁰. The combustion chamber L extends beneath the tubes J and the heating gases pass into the inter tube space of the bank of tubes J from the space L. Baffles M, M', M², M³, M⁴, and M⁵ cause the gases entering the bank of tubes J to flow upwardly alongside of and across the tubes J, thence upwardly across the portions of the tubes F, D, and E at the left of the baffles M² and M³, thence over the top of the baffle M³ in the space between the tubes C, D, and E, and thence down across the portions of the tubes D, E, and F at the right of the baffles M², M³, thence into the bank of tubes H and downward alongside the tubes H at the left hand side of the baffle M⁵, and thence around the lower end of the baffle M⁵ and upward along the tubes H at the right of the baffle M⁵ to the outlet O. In so far as above described, the boiler shown comprises nothing novel with me, but, on the contrary, is a conventional form of the known type of boiler which it is the purpose of the present invention to improve.

In accordance with the present invention, I arrange a superheater in the space between the upper circulating tubes C and the lower circulating tubes D and E. The superheater is composed of U-shaped tube elements P having end portions P' extending through one side wall of the boiler housing. The body portions of the superheater elements P are horizontally disposed and parallel in direction to the axes of the drums A, B, and I.

Advantageously, as shown, the bodies of the elements P are of the well known Foster gilled tube type while the end portions P' are bare. The portion of the boiler housing wall through which the end portions P' extend is formed by a series of castings Q, one for each element P, with upper and lower apertures for the corresponding pair of end portions P'. Each casting Q is formed with a flange-like foot or base portion which rests on a metal sill Q² and a similar flange or head at its upper end. The outer wall is formed of castings Q similar to the inner castings and interposed between the heads of the members Q and the brick-work of the housing wall above them is a lintel plate advantageously made of rela-

tively short cast metal sections Q' . The space between the walls formed by the parts Q is filled with a suitable heat insulating material Q^3 such as Sil-o-cel. Externally of the boiler housing the upper element ends P'_1 are connected to the superheater outlet header P^5 while the lower element ends P'_2 are connected to the superheater inlet header P^6 . These headers, which are horizontally disposed and extend transversely to the axes of the drums A and B, are supported from the boiler housing through brackets P^7 to which they are clamped by clamping yokes P^8 . The boiler steam pipe K^{10} is connected to one end of the superheater inlet header P^6 , and the steam delivery pipe (not shown) is connected to the opposite end of the header P^6 . The legs of the elements P are spaced apart by interposed I-beams R , and the elements are supported at their ends remote from the headers and also intermediate their ends, on I-beams S suspended from the roof of the boiler housing by suspension bars or bolts S' . Advantageously, as shown, the bank of superheater elements P is divided into two approximately equal sections or groups by the upper end of the baffle M^3 which extends between the two sections. Any usual or suitable provisions may be made for removing furnace dust from the superheater elements.

The superheater boiler construction described possesses important advantages from the practical standpoint. In the type of boiler illustrated, the main or primary water circulation is from the steam and water drum B down through the tubes H into the drum G, thence up through the tubes J , the drum I, and from the latter through the tubes F back to the drum B. In addition, there is a secondary water circulation from the drum A to the drum B through the circulating tubes E and from the drum B to the drum A through the tubes D . Steam flows from the drum B, in which is the main steam disengaging surface of the boiler, into the outlet drum A through the tubes C . The described circulation permits of the delivery of steam from the drum A through the steam pipe K^{10} , which is not only quite dry but is somewhat superheated, even when the boiler is being forced or operated at a capacity much above its normal rating.

These characteristic features of the type of boiler shown, require the drums A and B to be separated widely enough so that all of the superheating surface required for the amount of superheat ordinarily desired, may be obtained with a wide shallow bank of superheater elements such as is formed by the single row of U-shaped elements shown. The character of the boiler baffling and the space provided between the superheater and the circulating tubes C insures a practically

uniform distribution of heating gas up-flow across the superheater elements between the drum A and the baffle M^3 and a corresponding distribution of down-flow across the superheater elements between the baffle M^3 and the drum B. This uniformity in distribution of the heating gases flowing vertically through the shallow horizontal bank of superheater tubes insures effective and approximately equal use of all portions of the superheating surface, and minimizes the amount of heating surface required for a given superheating effect and also avoids the tendency to excessive heat absorption and consequent overheating of a portion of the superheating surface such as occurs when the flow of the heating gases is unduly concentrated over a portion only of the superheater elements. The superheater elements exercise a gas spreading effect on the flow through those elements which not only contributes to the desired horizontal distribution of flow of the heating gases through the superheater elements, but also to a desirable horizontal distribution of flow past the tubes F, E, and D, as well as in the upper portion of the bank of tubes J.

Aside from what may be called the thermal advantages of the superheater arrangement just explained, the superheater arrangement is obviously desirable from a mechanical standpoint because of its simplicity, durability and accessibility for inspection, cleaning, or repairs. Access to the space between the bank of superheater elements and the circulating tubes C is made possible by the provision of the manhole openings X . When it becomes necessary, as may sometimes be the case, to renew a superheater element, the formation of the metallic portion of the housing wall to which the superheater end portions extend out of the sectional castings Q and the form of the sectional lintel plate Q' , make it possible to remove the element to be renewed in a relatively simple manner by cutting the ends of the element loose from the headers P^5 and P^6 , and breaking down a small portion of the brickwork of the housing wall immediately above the element.

In the preferred construction illustrated, the heating gases leaving the boiler proper through the outlet O , pass downward through an economizer U to the economizer outlet U' . The economizer U comprises a chamber or housing located alongside of, and as shown, directly in contact with the rear wall of the boiler housing. The economizer U , as shown, is of the known type of Foster economizer comprising a bank of horizontally disposed gilled tube elements U^2 connected at their ends by return bends (not shown) in such a manner as to provide multiple paths of flow each including tubes at successively higher levels between

the economizer inlet header U^3 and outlet header U^4 which delivers water to the boiler feed water inlet K.

While in accordance with the provisions 5 of the statutes, I have illustrated and described the best form of embodiment of my invention now known to me, it will be apparent to those skilled in the art that changes may be made in the form of the apparatus disclosed without departing from 10 the spirit of my invention as set forth in the appended claims and that in some cases certain features of my invention may be used to advantage without a corresponding 15 use of other features.

Having now described my invention, what I claim as new and desire to secure by Letters Patent, is:

1. In a superheater boiler, the combination 20 with horizontally disposed U-shaped superheater elements, of a housing wall comprising a pair of metal walls through which the ends of the elements extend, each formed in sections, one for each of said elements, 25 and insulating material between said walls.

2. In a superheater boiler, the combination with horizontally disposed U-shaped superheater elements, of a housing wall comprising a pair of metal walls through which the ends of the elements extend, and 30 each formed in sections, one for each of said elements, each section being formed with apertures through which the corresponding ends of the element project, and insulating material between said walls. 35

3. In a superheater boiler, the combination with horizontally disposed U-shaped superheater elements of a housing wall comprising a pair of metal walls through which the ends of the elements extend, each wall 40 formed in sections, one for each of said elements, insulating material between said walls and a sectional lintel plate resting on top of said sections and brickwork supported on said lintel plates. 45

Signed at New York city, in the county of New York and State of New York, this 29th day of March, A. D., 1924.

WALTER FRANCIS KEENAN, JR.
